FIG. 1 is a perspective view of a dispenser cap showing my new design, in association with a broken line fragmentary showing of a container for illustrative purposes;

FIG. 2 is a top plan view;

FIG. 3 is a left side elevational view;

FIG. 4 is a front elevational view;

FIG. 5 is a right side elevational view;

FIG. 6 is a bottom plan view; and

FIG. 7 is a sectional view taken generally along lines 7—7 of FIGURE 3.

The characteristic features of the design are shown in full lines and reside essentially in the particularly configured, partially striated and oppositely disposed finger receiving projections.

This application is a continuation of my copending application D. 3,009 filed July 11, 1966 and now abandoned.
